COG COVER FOR SELF-PROPELLED ROTARY LAWNMOWER

Larry Monroe Cognata, Nashville, Tenn., assignor to
The Murray Ohio Manufacturing Company

Filed Sept. 17, 1974, Ser. No. 506,851

Term of patent 14 years

Int. Cl. D15—03

U.S. Cl. D40—1 A

Fig. 1.

Fig. 2.

Fig. 5.

FIG. 1 is a front perspective view of a cog cover for a self-propelled rotary lawnmower showing my new design;
FIG. 2 is a top plan view thereof;
FIG. 3 is a rear elevational view thereof;
FIG. 4 is a front elevational view thereof; and
FIG. 5 is a side elevational view thereof, partially in section.

I claim:

The ornamental design for a cog cover for a self-propelled rotary lawnmower, substantially as shown.
